UNITED STATES PATENT OFFICE.

BLOOMFIELD BROWER, OF NEW YORK, N. Y.

IMPROVEMENT IN STATIONARY CASES.

Specification forming part of Letters Patent No. 147,895, dated February 24, 1874; application filed January 23, 1874.

To all whom it may concern:

Be it known that I, BLOOMFIELD BROWER, of New York, in the State of New York, have invented a new and Improved Stationary Case, of which the following is a specification:

The nature of my invention consists in the construction of a case for calendar-cards, &c., made in one piece, and open at the back and bottom to prevent the collection of dirt or dust.

In the accompanying drawing, Figure I represents a front view of my improved case, and Fig. II the same view with the calendar-cards removed. Fig. III is a cross-section of the same, and Fig. IV a top view.

A A are the side pieces of the case, which are recessed to suit the three sets of cards for the days, months, and dates. These sides A A are connected together at the lower end of each recess by the cross bars or pieces n n n, and at the top by the cross-bar m, which latter may be arranged with a suitable opening or hole, w, for the purpose of hanging this skeleton-case upon a nail, if desired. The central parts n' of the cross-bars n are slightly raised to confine the lower edges of the cards. On the front of the side pieces A A small projecting flanges C C, in a line with the cross-bars n, are made on each side to confine the side edges of each pack of cards. On the back

one or more braces, D D, are arranged, suitably recessed, for the cards to rest upon, and to confine the same at their back, and connected with the cross-bars m n n n.

A stationary case constructed in the above-described manner is free from all objections to the present tin or wooden case, no dirt or dust can collect in the same, as the back and bottom of the same are quite open, and this case can be made of cast iron or metal, cast in one piece, and can be produced at a very small cost. In the same manner cases can be constructed having only one recess; but, when used for calendar-cards, the cards will then be required, with an extra length of card-board, to reach to the bottom of the case, whereby the expense would be considerably increased.

What I claim as my invention, and desire to secure by Letters Patent, is—

The herein-described skeleton stationary case, consisting of the sides A A, cross-bars n n n and m, projecting side pieces C C, and recessed braces or bars D D, substantially as set forth.

BLOOMFIELD BROWER.
